UNITED STATES PATENT OFFICE.

JEAN A. ROCHE, OF DAYTON, OHIO.

GUY-WIRE FITTING.

1,329,478.

Specification of Letters Patent.

Patented Feb. 3, 1920.

Application filed April 24, 1919. Serial No. 292,320.

To all whom it may concern:

Be it known that I, JEAN A. ROCHE, a citizen of the United States, residing at Dayton, in the county of Montgomery and 5 State of Ohio, have invented certain new and useful Improvements in Guy-Wire Fittings, of which the following is a specification.

This invention relates to a guy wire fitting for airplanes, and is intended to be used as the fitting to which the ends of the struts are fastened and to which the diagonal bracing wires are secured.

The object of the invention is to provide a 15 fitting which will permit the guy wire a small degree of movement in all directions, and yet does not use the usual two-way pivot connection.

It is a further object of this invention to 20 provide a guy wire fitting in which no turn buckle need be used and yet which may readily be tightened up by turning the guy wire itself.

The elimination of the two-way pivot 25 connection and the elimination of the turn buckle gives a simpler, cheaper and stronger construction, which presents much less head resistance on account of the elimination of these elements. Since several dozen guy 30 wire fittings must be used on the average plane, it is important that the head resistance of each fitting be made as small as possible.

Other objects and advantages will appear 35 as the description proceeds.

In the drawings illustrating certain embodiments of my invention, Figure 1 is a view in side elevation of my improved guy wire fitting, the plate forming part of the 40 fitting being shown broken away; Fig. 2 is an edge view of the same; Fig. 3 is a top view; Fig. 4 is a section on the line 4—4 of Fig. 3; Fig. 5 is a section on the line 5—5 of Fig. 3; Fig. 6 is a section on the line 6—6 45 of Fig. 4; Fig. 7 is a view showing two fittings as associated with the strut mounting; Fig. 8 is a view similar to Fig. 1 of a modification; Fig. 9 is a top view of Fig. 8; Fig. 10 is a view of another modification; 50 Figs. 11 and 12 are front and side views, respectively, of a stranded cable and the special eye bolt used therewith.

The plate forming the body of the fitting comprises a body portion 1 that is bolted by 55 bolts 2 and 3 to a wing beam 4. This body portion is provided with upwardly bent

arms 5 and 6, which are provided with a longitudinally extending slot 7, this slot being defined by the legs 8 and 9 of the arm 5. It should be understood that the fitting on 60 the arm 6 is a duplicate of that on the arm 5 and accordingly only that fitting on the arm 5 will be described.

An elliptically shaped or olive shaped element 10, provided with slots 11 and 12 cut 65 therein so as to be bifurcated at each end is brazed or welded on the end of the arm 5 and across the slot 7, the bifurcations 13 and 14 engaging over the legs 8 and 9. The top edges 15 and 16 of the legs 8 and 9 are 70 respectively rounded off so as to present the same curvature as the upper edge 17 of the element 10, which element 10 will hereafter be called an olive, the edges 15 and 16 being flush with the upper edge 17 of the olive. 75

The purpose of making the olive 10 tapered at both ends is to minimize the air resistance, the olive 10 being more or less stream lined in shape.

The olive 10 has drilled therein a conical 80 aperture 18, which extends most of the way therethrough. A spherically shaped seat, the rounded wall of which is indicated at 19 is drilled in the olive from the other side, so that the spherical seat and the conical 85 aperture register with one another to provide an opening all the way through the olive through which the threaded guy wire 20 passes. The shoulder defining the spherical aperture is indicated at 21. 90

The spherical surface 19 serves as a seat for a ball nut 22, the upper part of which is rounded off so as to fit snugly against the surface 19. The ball nut 22 is internally threaded to engage with the threaded portion of the guy wire 20. The ball nut 22 is provided with the usual flat faces 22' and is of such a size that it will only turn a very small amount within the slot 7 before it engages with the walls of said slot to prevent 100 further rotation thereof.

It will accordingly be seen that the guy wire may be tightened up by simply turning the wire itself, during which operation the nut 22 will be held from turning and so 105 a turn buckle adjustment will be had without the use of a turn buckle. After the guy wire 20 has been sufficiently tightened up by its being turned it is locked in its final position by a wire 23 passing through the 110 hole 24 in the end of the guy wire 20 and fastened around the leg 8 of the plate 5.

The other end of the guy wire being similarly fastened but provided with a thread of opposite sense *i. e.* one end of the guy wire has a right hand thread, the other end has a 5 left hand thread.

It is evident that the use of the conical aperture 18, the coöperating ball nut and spherical seat therefor, and the small clearance between the nut and the edges of the 10 slot provide a mounting for the guy wire which permits of a small degree of adjustment in all directions, a universal movement which allows the wire to take its proper alignment and allows vibration within suitable limits.

The part forming the main body of the guy wire 20, indicated at 25 is preferably, according to the well known practice, stream lined.

20 Referring now to Fig. 8, a modification is shown in which the olive 10 is provided with an additional slot 26 drilled in its side as shown, the purpose of this slot being to permit a quick release of the guy wire 20 from 25 the olive. In order to effect this release the nut 22 is loosened up slightly or the bolts 2 and 3 are loosened up slightly after which the ball nut 22 may be pushed off its seat and the threaded portion may be detached 30 from the olive. A lock nut, 22^a may be used here to lock the nut 22, to prevent loss of length adjustment when the wire is out of the fitting.

Fig. 10 shows a slight modification 35 adapted for the use of double guy wires. In this case it will be understood that the mounting for each wire is a substantial duplicate of the mounting for the wire shown in the other figures.

40 That is to say two conical apertures 27 and 28 will be provided, as well as two ball nuts 29 and 30, and coöperating spherical seats therefor. The guy wires 20 will each be tightened up by turning the same and 45 may be locked by a wire 31 passing through holes 24 in the ends of the respective wires, the ends of the locking wire being secured to each other as shown.

While I have shown the olive 10 made in 50 a separate piece from the plate 5, it should be understood that these said parts may be made integral, that is to say that they may be drop forged at a single operation. This feature is important in that the fitting may 55 be very cheaply and quickly produced.

The fact that the ball nut 22 acts to hold the wire in place and also coöperates in giving a turn buckle adjustment, without the use of a turn buckle, saves the weight 60 and head resistance of a turn buckle, clevis pin and cotter pin, is an important point of my invention.

The fact that part of the wire 20 and most of the ball nut 22 is within the slot 7 tends 65 to minimize the air resistance of these parts.

The curved or stream lined shape of the olive 10 is also of importance in minimizing the head resistance.

The plate 1 may be provided with suitable strut socket mounting means such as a 70 rounded head 32 provided with a hole 33, over which engages a strut socket 34, in which socket is seated the usual strut 35. A pin 36 may pass through the hole 33, to fasten the strut socket 34 to the head 32, 75 this mounting giving the strut a certain freedom of adjustment.

My guy wire fitting may be used with any 80 of the four common types of tension members used on airplanes, that is, with cables, wire, round tie rods and stream lined tie rods, and the claims should be interpreted accordingly.

In Figs. 11 and 12, I have shown a 85 stranded cable and a special eye bolt for attaching it to the guy wire fitting. This eye bolt comprises a shank 37, threaded at 38, and provided with a hole 39. The other end of the eye bolt is provided with two pairs of bifurcations, the elements 40, 40 forming 90 one pair, the element 41, together with a second similar element, not shown, forming the other pair. A bar 42 is made integral with or is brazed or welded between the two pairs of bifurcations, and together with 95 them, forms a mounting for the eye 43 formed in the end of the cable 44. The threaded portion 38 corresponds to the already described threaded portion 20 and engages with ball nut 22. Hole 39 is for a 100 locking wire corresponding to locking wire 23, Fig. 1.

While I have illustrated certain embodiments of my invention, it should be understood that it may be carried out in other 105 ways, as defined within the scope of the following claims.

I claim:—

1. A guy wire fitting, comprising a plate provided with a slot in the end thereof, a 110 guy wire seat fastened to the end of the plate to extend across the said slot, said seat being provided with an aperture in registry with said slot, said aperture being shaped so as to allow the guy wire a universal move- 115 ment.

2. A guy wire fitting, comprising a plate provided with a slot in the end thereof and a guy wire seat fastened to the end of the plate to extend across the said slot, said guy 120 wire seat being provided with an aperture therethrough registering with said slot.

3. The combination as claimed in claim 2, said aperture being of increasing size outwardly.

4. The combination as claimed in claim 2, said guy wire seat being further provided with a recess for a nut seat, said aperture and said recess being in registry.

5. A guy wire fitting, comprising a plate 130

- provided with a slot in the end thereof and a guy wire seat fastened to the end of the plate to extend across the said slot, said guy wire seat being provided with a shouldered 5 aperture therethrough, the shoulder of the aperture acting as a seat for a nut. 40
6. A guy wire fitting, comprising a plate provided with a slot in the end thereof and a guy wire seat fastened to the end of the 10 plate to extend across the said slot, said guy wire seat being provided with an aperture that is narrowed for a part of its length and which then expands, the expanded portion serving as a seat for a nut. 45
- 15 7. A guy wire fitting, comprising a plate provided with a slot, and a slotted guy wire seat fastened to extend across the said slot, said plate engaging in the slot of said slotted guy wire seat. 50
- 20 8. A guy wire fitting, comprising a plate provided with a slot, and a guy wire seat slotted at each end, said plate engaging in the slots of said slotted guy wire seat. 55
- 25 9. The combination as claimed in claim 1, said guy wire seat being stream lined. 60
10. A guy wire fitting, comprising a plate provided with a slot in the end thereof, and a stream lined guy wire seat fastened to the end of said plate to extend across the slot, 30 said seat being provided with an aperture therethrough in registry with the slot. 65
11. A guy wire fitting, comprising a plate provided with a slot in the end thereof, and a stream lined guy wire seat fastened to the 35 end of said plate to extend across the slot, said seat being provided with a tapered aperture therethrough in registry with the said 70
13. In combination, a plate provided with a slot in the end thereof, a guy wire seat fastened to the end of said plate to extend across the slot in said plate, said guy wire seat being provided with an aperture therethrough in registry with said slot, said guy wire seat further being provided with a shoulder extending into said aperture, a guy wire passing through said aperture and extending into said slot, and a nut on the end of said guy wire adapted to engage against said shoulder. 50
14. In combination, a plate provided with a slot in the end thereof, a guy wire seat fastened to the end of said plate to extend across the slot in said plate, said guy wire seat being provided with a tapered aperture therethrough in registry with said slot, said guy wire seat further being provided 55 with a curved shoulder extending into said aperture, a guy wire passing through said aperture and extending into said slot and a ball nut on the end of said guy wire adapted to engage against said curved shoulder. 65
15. The combination as claimed in claim 13, said guy wire seat being stream lined. 70
- In testimony whereof I affix my signature.
JEAN A. ROCHE.
